DOOR LOCK

John H. Roethel, Coral Gables, Fla., assignor to Roethel Engineering Corporation, Detroit, Mich., a corporation of Michigan

Application July 27, 1953, Serial No. 370,494

13 Claims. (Cl. 292—280)

This invention relates to latch mechanism for swinging doors, especially the doors of automobile or other vehicle bodies, an object of the present invention being to provide an improved door latch mechanism which will effectively meet various requirements for motor vehicle door locks yet which is characterized by simplification and compactness in construction and which is relatively small, easy and economical to manufacture, comparatively quiet in operation, efficient and durable in use.

The present invention is embodied in an improved door latch mechanism comprising a rotatable latch device, such as a rotary gear-type bolt, mounted on one side of the latch support, a pivoted detent or dog means co-operable therewith mounted on the same side of the latch support, improved outer and inner manually operable actuating means for swinging or pivotally actuating the detent or dog means to disengage the same from said latch device, and improved control means for selectively controlling the effectiveness of the actuating means in the actuation thereby of the detent or dog means, the operative elements of said actuating means and the control means being associated with a side of the latch support angularly related to said one side.

More particularly the present invention is embodied in an improved door latch mechanism comprising a support having two angularly related plate portions, a rotatable latch device, such as a gear type bolt and ratchet means, mounted on one plate portion of the support, detent means pivotally mounted on said one plate portion and engageable with said latch device for holding the same in door latching position, said detent means having an arm extending toward said other plate portion of the support, outer manually operable means for pivotally actuating said detent means to disengage the same from said latch device and including a slidable member movably disposed in a detent actuating position. In the illustrated construction the slidable member is mounted on a carrier pivotally mounted on said other plate portion and constructed to provide for slidable movement of said slidable member relative thereto. There is also provided an inner manually operable means including a pivoted member on said other plate portion connected to said slidable member to swing the same from said detent actuating position to a second position in which position said outer manually operable means is ineffective to actuate said detent means, and a second pivoted member on said other plate portion having a part engageable by said detent arm and adapted to be swung thereby upon rotative movement of said latch device, such as occurs upon the latch bolt engaging the striker or keeper as the door is moved from an open to a closed position, said second pivoted member having a part disposed in position to swing said slidable member from said second position to said detent actuating position upon said rotative movement of the latch device.

Further objects and features of the particular embodiment

2

ments of the invention herein illustrated will appear in the following description, reference being had to the accompanying drawings forming a part of the specification wherein like reference numerals designate corresponding parts in the several views.

Fig. 1 is a fragmentary side elevation of a portion of an automobile body provided with swinging doors upon which latch devices made in accordance with the present invention are installed.

10 Fig. 2 is a fragmentary sectional elevation taken substantially through lines 2—2 of Fig. 3 looking in the direction of the arrows and illustrating one embodiment of the present invention.

15 Fig. 3 is an elevation looking in the direction of the arrows 3—3 of Fig. 2.

Fig. 4 is a section taken substantially through lines 4—4 of Fig. 3.

Fig. 5 is a view similar to Fig. 3 illustrating certain of the parts in a different operative relationship.

20 Fig. 6 is a fragmentary elevation in part similar to Fig. 3 illustrating a second embodiment of the present invention.

Fig. 7 is a sectional elevation illustrating the rotary latch bolt and striker or keeper in their relative positions when the door is fully closed.

Fig. 8 is a view in part similar to Fig. 3 illustrating a further embodiment of the present invention.

Fig. 9 is an elevation looking in the direction of the arrows 9—9 of Fig. 8.

30 Fig. 10 is a section taken substantially through line 10—10 of Fig. 10 looking in the direction of the arrows.

This application is a continuation in part of application Serial No. 286,487, filed May 7, 1952, now abandoned.

35 Before explaining in detail the present invention it is to be understood that the invention is not limited in its application to the details of construction and arrangements of parts illustrated in the accompanying drawings, since the invention is capable of other embodiments and

40 of being practiced or carried out in various ways. Also it is to be understood that the phraseology or terminology employed herein is for the purpose of description and not of limitation.

45 In the drawings there is illustrated, by way of example, particular embodiments of the present invention as applied to the doors and frame structures of an automobile. The latch device in the embodiment of the invention shown in Figs. 1 to 5 inclusive comprises a case

50 plate 10 provided with screw bosses 10a by means of which the case plate is secured to the inner side of the jamb portion of a vehicle door. The case plate 10 terminates at its inner edge in a flange 11 provided with screw bosses 11a by means of which the flange is adapted

55 to be secured to the inner panel of the door. The latch device is preferably provided with a rotatable toothed latch or bolt 12 positioned at the outer face of the case plate 10, this latch or bolt having an integral projecting shaft or shank 13 extending through an aperture in the case plate, the edge of the aperture being suitably formed

60 to provide a bearing for the bolt shank. The inner end of the shank 13 is flattened and extended through a correspondingly shaped aperture in a rotatable toothed detent engaging member or ratchet member 14 and is riveted thereto.

65 The rotatable latch, as best viewed in Fig. 7, is formed with a number of radially projecting tooth-like projections 12a, preferably five, which are spaced equally around the periphery of the latch so as to provide in effect a gear type latch or bolt. The ratchet member 14 is also formed around its periphery with a number of tooth-like abutments or projections 14a which corre-

spond in number to the tooth-like projections 12a of the bolt.

Pivots mounted on a shoulder rivet 15 secured to the case plate 10 is a swinging detent, pawl or dog 16. The detent, pawl or dog 16 is pivots mounted on the stud or rivet 15 near the outer edge of the plate 10 and extends in a substantially horizontal direction toward the flange 11; the end 17 of the detent projecting through an aperture 18 in the flange 11 for a short distance therebeyond. The detent 16 has a downwardly extending arm or projection 19 cooperable with the teeth or projections 14a of the ratchet member 14. This detent arm or projection 19 is engageable with any one of the teeth 14a in the manner shown in Fig. 2 to hold the ratchet member and, hence, the bolt 12 in locking position against rotation in a counterclockwise direction as viewed in Fig. 2. The detent 16 is adapted to be swung upwardly by mechanism, hereinafter described, actuatable by outside and inside operators, also hereinafter described, so as to raise the detent arm or projection 19 out of engagement with any one of the ratchet teeth 14a. It will be understood that when the door is moved from an open to a closed position, the bolt 12 is rotated by engagement with its striker or keeper in a clockwise direction as viewed in Fig. 2. The configuration of the ratchet teeth 14a is such that the pivoted detent 16 is unable to restrain rotation thereof in a clockwise direction but instead the detent is pivots actuated upwardly in a disengaging direction of movement.

Associated with the detent 16 is a multi-armed actuating lever, generally designated 20, which is pivots upon a shoulder rivet 21 secured to the case plate flange 11. An arm 22 of the multi-armed actuating lever 20 extends from the pivot axis thereof toward the case plate 10 and has an interlocking connection with the end 17 of the detent 16 so that the actuating member 20 and the detent 16 are operatively associated with each other, each being responsive to movement of the other.

It is preferable that the detent 16 be spring urged into engagement with the ratchet 14 to ensure that the two are properly meshed after each disengagement of the detent from the ratchet. In the illustrated embodiment of the invention this is accomplished through the medium of a coil spring 23 anchored at its inner end to a retainer 24 lanced out of the case plate flange 11. This spring 23 has a horizontally extending arm 25 engageable with the lower edge of an arm 26 of the multi-armed actuating lever 20. The spring arm 25 tends to urge the arm 26 upwardly and the actuating member 20 in a counterclockwise direction as viewed in Fig. 3. The resulting downward urging of the arm 22 results, due to the interlocking connection between the arm 22 and the detent 16, in the detent arm or projection 19 being yieldingly urged toward the ratchet 14.

In accordance with the present embodiment of the invention means operable from the outside of the door is provided for pivots actuating the multi-armed actuating lever 20 to swing the same in a clockwise direction as viewed in Fig. 3 and thereby cause the arm 22 to swing the detent 16 upwardly out of engagement with the ratchet 14. Referring to Fig. 4 a fragmentary portion of a shaft 27 is shown. The shaft 27 is preferably associated with a push button 28 slidably mounted in the outside door handle 29 (Fig. 1) and is bodily shiftable therewith in a longitudinal direction. Motion from the push button 28 and the shaft 27 is transmitted to the detent 16 through the medium of a transmitting or detent actuating member 30 which is pivots supported or mounted in such a manner that it may be swung into or out of operative association with an upwardly extending arm 31 of the actuating member 20. Referring to Figs. 3 and 4, a carrier member 32 having side flanges 33 extending partially lengthwise thereof is pivots mounted intermediate its ends on a shoulder stud or rivet 34. A bell crank lever 35 is pivots mounted at

one end of the carrier member 32 on a shaft 36 journalled in the flanges 33 of the carrier member. The bell crank lever 35 which is substantially equal in thickness to the distance between the carrier flanges 33 is provided on one leg thereof with a flange 37 adapted to remain in contact with the adjacent end of the shaft 27 within the range of swinging movement of the carrier. The other leg of the bell crank 35 is bifurcated, the bifurcated portion 38 journalling a shaft 39 which extends beyond the edges thereof. The transmitting or detent actuating member 30 is also provided with side flanges 40 extending partially lengthwise thereof. The outer ends of the shaft 39 are journalled in the transmitting or detent actuating member flanges 40 at the outer end thereof, thereby pivots connecting the transmitting or detent actuating member 30 to the bell crank lever 35. From the foregoing it will be apparent that when the push button 27 is shifted in the direction of the arrow, see Fig. 4, the bell crank lever 35 will be pivots in a counterclockwise direction causing the transmitting or detent actuating member 30 to be shifted longitudinally relative to the carrier 32 in the direction of the actuating member arm 31. A suitable coil spring 41 is wound about the pin or shaft 39 and has one end thereof in contact with the leg 37 of the bell crank 35 and the other end thereof engaging the base portion of the transmitting member 30, the spring 41 yieldingly urging the transmitting member and bell crank lever toward normal inoperative position.

The carrier member 32 is provided with an extending portion 42 which projects through an aperture 43 in a flange 44 of the actuating member arm 31. The transmitting member 30 is provided with a projection or abutment 45 adapted to engage or abut the section 46 of the flange 44 when the carrier member 32 and transmitting or detent actuating member 30 are in the position shown in Fig. 3. When the carrier member 32 and transmitting or detent actuating member 30 are in the position shown in Fig. 5, the projection or abutment 44 is adapted to pass unhindered through the aperture 43. The detent actuating member 30 will be unable to cause pivotal movement of the actuating member 20 and therefore no disengagement of the detent 16 will occur.

The present latch device is preferably operated from the inside of the door through the medium of a remote control mechanism (not shown) adapted to pivots actuate a lever 47. This lever is pivots on the shank of a shoulder rivet 48 secured to the case plate flange 11. Referring to Fig. 3, it will be noted that the actuating lever 20 has an upwardly extending arm 49. The lever 47 is provided with a lug or projection 50 adapted to abut the arm 49 upon swinging movement of the lever 47 in a counterclockwise direction, thereby swinging the actuating lever 20 and the arm 22 in a clockwise direction of movement resulting in the detent 16 being lifted out of engagement with the ratchet 14.

Reference has been made to the construction and arrangement of the transmitting or detent actuating member 30 and the carrier member 32 whereby the transmitting or detent actuating member may be swung to place the projection or abutment 45 thereon into and out of abutting relation to the flange section 46 on the actuating member arm 31. In accordance with the present embodiment of the invention means operable from the inside and outside of the door are provided for pivots swinging the transmitting or detent actuating member 30 into and out of operative relation to the actuating lever arm 31, this being accomplished in the present instance by swinging the carrier member 32 about its pivot 34. The means operable from the inside of the door for swinging the transmitting member or detent actuating member 30 and carrier member 32 about the pivot axis 34 comprises a lever 51 pivots mounted on the same stud 21 which pivots secures the actuating member 20 to the flange 11. The lever 21 has an up-

wardly projecting arm 52 provided with a flange 53 thereon. The flange 53 is provided with an aperture 54 through which the extension 42 of the carrier member 30 extends. A vertically shiftable rod or plunger 55 is pivotally connected at 56 to the arm 52 of lever 51. The rod 55 extends upwardly through the garnish molding at the inner side of the glass panel of the door and carries at its upper end a knob 57. The knob 57 may be manipulated at the inside of the door to shift the rod 55 vertically in either direction, thereby rocking the lever 52 and causing the carrier member 30, because of the interlocked relation between the extension 42 thereof and the flange 53 of the lever 52, to be swung from the position shown in Fig. 3 to the position shown in Fig. 5 and vice versa. By thus swinging the carrier member 30 through the medium of the lever 52 the transmitting or detent actuating member 30 will be correspondingly swung from its position shown in Fig. 4 to the position shown in Fig. 5 and vice versa. The carrier member 32 is yieldingly held in either of its positions shown in Figs. 3 and 5 by means of a snap-over spring 58 of suitable strength attached at one end to an extension 59 of the carrier member 32 and at its opposite end to the case plate flange 11. When the transmitting or detent actuating member 30 and carrier member 32 are swung to the position shown in Fig. 5, the limit of this swinging motion is governed by the length of the aperture 43 in the flange 44 of the actuating member arm 31.

The front doors of vehicles are generally equipped with key operated devices operable from the outside of the vehicle for placing the lock mechanism in locked condition. The shaft 27 is adapted to be turned by such a key operated device and, as best viewed in Fig. 5, the end thereof is received in a rectangular aperture 60 in a cam member 61 pivotally mounted on the flange 11. The cam member 61 is provided with a substantially V-shaped recess 62 in one side thereof adapted to receive a lug or tongue 63 on the adjacent end of the carrier member 32. It will be noted that the width of the recess 62 is substantially greater than the width of the tongue or lug 63 in order to provide a lost motion connection. The lost motion connection is necessary in order to permit the key of the key operated device to be returned to a vertical position for withdrawal from the device after having been used to turn the shaft 27.

An important feature of the present invention is the provision of means for utilizing pivotal movement of the actuating member 20 to restore the transmitting member 30 from the position shown in Fig. 5 to the Fig. 3. It will be noted that the actuating member 20 may be pivotally actuated in either one of two ways regardless of the operativeness or effectiveness of the outer manually operable means to do so. The actuating member 20, in the present embodiment, is at all times responsive to swinging movement of the lever 47 actuatable through manipulation of the inside door handle. In addition, the actuating member 20 is responsive to pivotal movement of the detent means 16 resulting from rotation of the latch bolt as it engages the striker or keeper.

In the present embodiment, the transmitting member 30 is provided with a lug 64 turned downwardly toward the flange 11. When the transmitting member 30 is in the position shown in Fig. 5, the lug thereon lies in the path of swinging movement of the rounded end 65 of the actuating lever arm 49 and upon pivotal movement of the actuating lever 20 in a clockwise direction, the end 65 will abut the lug 64 and urge the transmitting or detent actuating member 30 and its carrier member 32 from the position shown in Fig. 5 to the position shown in Fig. 3.

However, on occasion it is convenient to be able to open the vehicle door, then to depress the push button 57 to place the lock mechanism in locked condition

and then to close the door without having the lock mechanism restored to unlocked condition, i. e., without having the transmitting or detent actuating member restored from the position shown in Fig. 5 to the position shown in Fig. 3. In the present embodiment, it is only necessary during the closing movement of the door that the push button be held inwardly thus causing the transmitting member 30 to be shifted longitudinally and the lug 64 to be displaced out of the path of swinging movement of the rounded end 65 of the actuating member arm 49. With the lug 64 so displaced, no restoring movement of the transmitting or detent actuating member 30 will occur.

The embodiment of the invention shown in Fig. 6 illustrates a preferred construction for adapting the lock structure shown in the embodiment of Figs. 1 to 5 for use on vehicle doors, usually the rear doors, not equipped with key actuated means for locking the door, the locking of the door being accomplished solely through manipulation of the garnish molding push button 57. In the present embodiment such manipulation of the push button is adapted to render not only the outside operator or push button 28 ineffective to cause disengagement of the detent means 16 from the ratchet 14 but also simultaneously to render the inside operator ineffective to do so. It will be remembered in the previous embodiment that the actuating lever 20 was at all times responsive to pivotal movement of the lever 47. Accordingly, in the present embodiment the lever 47 is provided with an upstanding lug 66 and the lever 51 swingable by manipulation of the push button 57 is provided with an additional arm 67. Thus, when the lever 51 is swung in a clockwise direction, as viewed in Fig. 6, to place the transmitting or detent actuating member 30 in inoperative position relative to the actuating member arm 31, the arm 67 thereof will be swung into abutting position relative to the lugs 66 on the lever 47, thereby blocking the swinging movement of the same necessary to cause detent disengaging movement of the actuating lever 20. Thus, with the lever 51 in a position corresponding to the position in which it is shown in Fig. 5, the door can only be unlocked by shifting the rod or plunger 55 upwardly so as to restore the lever 51 to its position shown in Fig. 6.

It will be noted that in the present embodiment the actuating member arm 49 does not have the rounded end 65 thereon. The elimination of the rounded end 65 of the arm 49 provides an arrangement wherein the parts of the lock mechanism may be placed in locked condition when the door is open and the door may be closed without the necessity of depressing the outside operator to prevent restoration of the lock mechanism parts to unlocked position. It will be apparent that there is no particular need for such a restoration structure on the rear doors of the vehicle in the absence of any key operated means for locking such doors.

There is illustrated in Figs. 8 to 10 inclusive a preferred construction of the lock embodying the present invention for use with a door arrangement wherein the key locking cylinder mechanism is mounted on the door panel in spaced relation to the door handle. In this embodiment the lever 51 is provided with an arm 81. This arm 81 extends toward the left hand corner of the flange 11, as viewed in Fig. 8, and is provided with a bifurcated portion 81a on the end thereof. Slidable within the bifurcated portion 81a is an upturned lug 82 on the upper end of a crank arm 83 pivoted at its lower end to the plate 11 on a tubular pivot stud 84, the pivot stud being provided with a rectangular opening or socket to receive the key actuated shaft which is connected to the cylinder mechanism of any conventional lock having the usual key control. By turning the key in the lock in the outside of the door the crank arm 83 may be swung to rock the lever 51 in either direction.

to thereby render the actuating member 30 operative or inoperative to disengage the detent from the latch device.

In the present embodiments of the invention the rotary toothed latch or bolt 12 is actuated when the door is closed by means of a striker or keeper member 68. In general, the keeper or striker comprises a C-shaped structure having upper and lower body portions 69 and 70. The lower body portion 70 is formed at its lower edge with two integral depending tooth-like projections 71 and 72 with which the teeth 12a of the latch bolt 12 mesh to hold the door in either final or safety locking position. When an adjacent pair of teeth 12a embrace and engage the tooth 72 the bolt is in safety locking position, and when an adjacent pair of teeth 12a embrace the tooth 71, as shown in Fig. 7, the bolt is in final locking position.

The upper surface 73 of the lower body portion 70 forms an inclined ramp engageable by a suitably contoured dovetail or abutment 74 fastened to the outer face of the case plate 10. A yieldable wedging means is carried on the underside of the upper body portion 69 of the striker device and engages the upper surface of the dovetail or abutment 74 to firmly hold the door against vibratory movement in a vertical plane. The wedging means in the present instance comprises a wedge block 75 controlled by a compression spring 76, the wedge block and spring being slidably retained within a recess 77 by means of a guide rod 78 fastened to the end walls of the recess 77. The spring 76 is mounted under initial compression and constantly urges the wedge outwardly or to the right as viewed in Fig. 7. During closing movement of the door the wedge block 75 is engaged by the upper surface of the dovetail and is carried inwardly to some extent against the action of the spring. As the vehicle body vibrates during vehicular motion, the wedge block will constantly tend to tighten itself against the upper surface of the abutment 74 and, hence, maintain the bolt 12 firmly in engagement with the tooth 71 on the striker thus minimizing the possible vibratory movement of the door in a vertical direction.

The lock mechanism construction and arrangement embodied in the present invention has an important advantage in that the mechanism is virtually tamper-proof. When the lock is mounted within the vehicle door the mechanism mounted on the flange 11 thereof is concealed between the inner door panel and flange 11 and the flange in turn is between the inner door panel and the window glass. Thus, it is virtually impossible to trip any part of the latch mechanism on the flange by working a wire or other tool down the window well for such purpose, a customary practice of persons seeking to break and enter into a vehicle. The mechanism on the case plate portion, such as the detent 16, is effectively shielded against such tactics by means of a simple cover plate 79 securely spot welded to the plate and covering most of the detent 16 and the ratchet 14.

I claim:

1. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having a projecting arm, means for pivotally actuating said detent means to disengage the same from said latch device and including a slidable member normally disposed in a detent actuating position, mounting means for said slidable member pivotally mounted on said other plate portion and constructed to provide for slidable movement of said slidable member relative thereto, a pivoted member on said other plate portion having a part disposed in opposing relation to a part of said slidable member when the latter is in said detent actuating position, said pivoted member having a second part connected to said detent arm, and outer manually operable means for shifting said slidable member to cause

5 said parts to abut and thereby cause said second part to swing said detent arm and pivotally actuate the detent means to disengage the same from said latch device, and inner manually operable means including a second pivoted member on said other plate portion connected to said slidable member mounting means to swing the same to move said slidable member from said detent actuating position to a second position in which said parts are disposed out of opposing relation.

10 2. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having a projecting arm, means for pivotally actuating said detent means to disengage the same from said latch device and including a slidable member normally disposed in a detent actuating position, mounting means for said slidable member pivotally mounted on said other plate portion and constructed to provide for slidable movement of said slidable member relative thereto, a pivoted member on said other plate portion having a part disposed in opposing relation to a part of said slidable member when the latter is in said detent actuating position, said pivoted member having a second part connected to said detent arm, and outer manually operable means for shifting said slidable member to cause said parts to abut and thereby cause said second part to swing said detent arm and pivotally actuate the detent means to disengage the same from said latch device, and inner manually operable means including a second pivoted member on said other plate portion connected to said slidable member mounting means to swing the same to move said slidable member from said detent actuating position to a second position in which said parts are disposed out of opposing relation, said first-named pivoted member having a second part disposed in position to swing said slidable member from said second position to said detent actuating position upon rotative movement of the latch device.

15 3. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having a projecting arm, means for pivotally actuating said detent means to disengage the same from said latch device and including a slidable member normally disposed in a detent actuating position, mounting means for said slidable member pivotally mounted on said other plate portion and constructed to provide for slidable movement of said slidable member relative thereto, a pivoted member on said other plate portion having a part disposed in opposing relation to a part of said slidable member when the latter is in said detent actuating position, said pivoted member having a second part connected to said detent arm, and outer manually operable means for shifting said slidable member to cause said parts to abut and thereby cause said second part to swing said detent arm and pivotally actuate the detent means to disengage the same from said latch device, and inner manually operable means including a second pivoted member on said other plate portion connected to said slidable member mounting means to swing the same to move said slidable member from said detent actuating position to a second position in which said parts are disposed out of opposing relation, an inner manually operable member pivotally mounted on said other plate portion for swinging said first named pivoted member to effect disengagement of said detent means from said latch device, and means on said second pivoted member movable into position to block pivotal movement of said inner manually operable member.

4. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having a projecting arm, means for pivotally actuating said detent means to disengage the same from said latch device and including a slidable member normally disposed in a detent actuating position, mounting means for said slidable member pivotally mounted on said other plate portion and constructed to provide for slidable movement of said slidable member relative thereto, a pivoted member on said other plate portion having a part disposed in opposing relation to a part of said slidable member when the latter is in said detent actuating position, said pivoted member having a second part connected to said detent arm, outer manually operable means for shifting said slidable member to cause said parts to abut and thereby cause said second part to swing said detent arm and pivotally actuate the detent means to disengage the same from said latch device, inner manually operable means including a second pivoted member on said other plate portion connected to said slidable member, mounting means to swing the same to move said slidable member from said detent actuating position to a second position in which said parts are disposed out of opposing relation, and a common means for pivotally mounting said pivoted members to swing about a common axis.

5. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having a projecting arm, means for pivotally actuating said detent means to disengage the same from said latch device and including a slidable member normally disposed in a detent actuating position, mounting means for said slidable member pivotally mounted on said other plate portion and constructed to provide for slidable movement of said slidable member relative thereto, a pivoted member on said other plate portion having a part disposed in opposing relation to a part of said slidable member when the latter is in said detent actuating position, said pivoted member having a second part connected to said detent arm, outer manually operable means for shifting said slidable member to cause said parts to abut and thereby cause said second part to swing said detent arm and pivotally actuate the detent means to disengage the same from said latch device, inner manually operable means including a second pivoted member on said other plate portion connected to said slidable member mounting means to swing the same to move said slidable member from said detent actuating position to a second position in which said parts are disposed out of opposing relation, an inner manually operable member pivotally mounted on said other plate portion for swinging said first named pivoted member to effect disengagement of said detent means from said latch device, means on said second pivoted member movable into position to block pivotal movement of said inner manually operable member, and a common means for pivotally mounting said pivoted members to swing about a common axis.

6. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means including a shiftable actuating member for pivotally

actuating said detent means to disengage the same from said latch device, means pivotally mounting said actuating member on said other plate portion for swinging movement from a first position to a second position, a transmitting member pivotally mounted on said other plate portion and coupled to said detent means arm, said actuating member when in said first position having a part adapted to engage a part on said transmitting member for shifting the latter and when in said second position having said parts free of inter-engagement, inner manually operable means mounted on said other plate portion for swinging said actuating member from said first position to said second position, said transmitting member being movable by said detent means independently of said actuating member upon rotative movement of said latch device, and means on said transmitting member adapted to abut the actuating member when in said second position to restore the latter to said first position.

7. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means including a shiftable actuating member for pivotally actuating said detent means to disengage the same from said latch device, means pivotally mounting said actuating member on said other plate portion for swinging movement from a first position to a second position, a transmitting member pivotally mounted on said other plate portion and coupled to said detent means arm, said actuating member when in said first position having a part adapted to engage a part on said transmitting member for shifting the latter and when in said second position having said parts free of inter-engagement, inner manually operable means mounted on said other plate portion for swinging said actuating member from said first position to said second position, said transmitting member being movable by said detent means independently of said actuating member upon rotative movement of said latch device, and means on said transmitting member adapted to abut the actuating member when in said second position to restore the latter to said first position.

8. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means including a shiftable actuating member for pivotally actuating said detent means to disengage the same from said latch device, means pivotally mounting said actuating member on said other plate portion for swinging movement from a first position to a second position, a transmitting member pivotally mounted on said other plate portion and coupled to said detent means arm, said actuating member when in said first position having a part adapted to engage a part on said transmitting member for shifting the latter and when in said second position having said parts free of inter-engagement, inner manually operable means including a lever pivotally mounted on said other plate portion for swinging said actuating member from said first position to said second position, said transmitting member being movable by said detent means independently of said actuating member upon ro-

tative movement of said latch device, said transmitting member having a part normally adapted to abut a part of said actuating member upon said transmitting member being moved by said detent means thereby to swing said actuating member from said second position to said first position, said actuating member when disposed in said second position being shiftable to move its said part out of abutting relationship to said transmitting member part, and a common means for pivotally mounting said lever and transmitting member to swing about a common axis.

9. In a latch mechanism for a swinging door, a support having two angularly related plate portions, a rotatable latch device mounted on one plate portion of the support, detent means pivotally mounted on said one plate portion and engageable with said latch device for holding the same in door latching position, outer manually operable means including a carrier member pivotally mounted on said other plate portion for swinging movement from a first position to a second position and vice versa, an actuating member mounted on said carrier member for swinging movement therewith from said first position to said second position and vice versa and also for shiftable movement relative thereto, and a transmitting member interposed between said actuating member and detent means and shiftable to pivotally actuate said detent means to disengage the same from said latch device, inter-engageable means on said transmitting and actuating members effective to permit shifting of the transmitting member upon actuation of the actuating member when the latter is in said first position, inner manually operable means including a lever pivotally mounted on said other plate portion for swinging said carrier member and actuating member from said first position to said second position and in which position said outer manually operable means is ineffective to actuate said detent means, said transmitting member being pivotally mounted on said other plate portion and being swingable by said detent means upon rotative movement of said latch device, said transmitting member having an arm disposed in position to swing said carrier and actuating members from said second position to said first position upon said transmitting member being swung by said detent means.

10. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means for pivotally actuating said detent means to disengage the same from said latch device, said outer manually operable means including a transmitting member operatively coupled to said detent means arm and also including a shiftable actuating member on said other plate portion having a part adapted in the operative position of the actuating member to engage a part on said transmitting member upon shifting the actuating member and thereby cause said transmitting member to pivotally move the detent means out of holding relation to said latch device, means for mounting said actuating member on said other plate portion for swinging movement from said operative position to an inoperative position in which said parts are free of engagement upon shifting said actuating member, inner manually operable means mounted on said other plate portion for swinging said actuating member from said operative to said inoperative position, said transmitting member being movable by said detent means independently of said actuating member upon rotative movement of said latch device, said transmitting member having an arm portion adapted to engage the actuating member when in said inoperative position to restore the latter to said operating position.

11. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means for pivotally actuating said detent means to disengage the same from said latch device, said outer manually operable means including a transmitting member operatively coupled to said detent means arm and also including a shiftable actuating member on said other plate portion having a part adapted in the operative position of the actuating member to engage a part on said transmitting member upon shifting the actuating member and thereby cause said transmitting member to pivotally move the detent means out of holding relation to said latch device, means for mounting said actuating member on said other plate portion for swinging movement from said operative position to an inoperative position in which said parts are free of engagement upon shifting said actuating member, inner manually operable means mounted on said other plate portion for swinging said actuating member from said operative to said inoperative position, said transmitting member being movable by said detent means independently of said actuating member upon rotative movement of said latch device, said transmitting member having a part normally adapted to abut a part on said actuating member upon said transmitting member being moved by said detent means thereby to swing said actuating member from said inoperative position to said operative position, said actuating member when disposed in said inoperative position being shiftable to move its said part out of abutting relationship to said transmitting member part.

12. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate portion of the support, outer manually operable means for pivotally actuating said detent means to disengage the same from said latch device, said outer manually operable means including a transmitting member operatively coupled to said detent means arm and also including a shiftable actuating member on said other plate portion having a part adapted in the operative position of the actuating member to engage a part on said transmitting member upon shifting the actuating member and thereby cause said transmitting member to pivotally move the detent means out of holding relation to said latch device, means for mounting said actuating member on said other plate portion for swinging movement from said operative position to an inoperative position in which said parts are free of engagement upon shifting said actuating member, inner manually operable means mounted on said other plate portion for swinging said actuating member from said operative to said inoperative position, said transmitting member being movable by said detent means independently of said actuating member upon rotative movement of said latch device and having means adapted to engage said actuating member upon such independent movement to restore said actuating member from said inoperative position to said operative position.

13. In a latch mechanism for a swinging door, a support having two angularly related plate portions, a rotatable latch device mounted on one plate portion of the support, detent means pivotally mounted on said one plate portion and engageable with said latch device for holding the same in door latching position, said detent means having an arm extending toward said other plate

portion of the support, outer manually operable means for pivotally actuating said detent means to disengage the same from said latch device, said outer manually operable means including a transmitting member operatively coupled to said detent means arm and also including a shiftable actuating member on said other plate portion having a part adapted in the operative position of the actuating member to engage a part on said transmitting member upon shifting the actuating member and thereby cause said transmitting member to pivotally move the detent means out of holding relation to said latch device, means for mounting said actuating member on said other plate portion for swinging movement from said operative position to an inoperative position in which said parts are free of engagement upon shifting said actuating member, inner manually operable means mounted on said other plate portion for swinging said actuating

member from said operative to said inoperative position, said transmitting member being movable by said detent means independently of said actuating member upon rotative movement of said latch device and having means 5 adapted to engage said actuating member upon such independent movement to swing said actuating member from said inoperative position to said operative position, said actuating member when disposed in said inoperative position being shiftable to move its said part out of abutting relationship to said transmitting member part.
